UNITED STATES PATENT OFFICE.

WILLIAM H. VON HACHT, OF VALLEJO, CALIFORNIA.

VALVE MECHANISM.

Application filed November 22, 1923. Serial No. 676,401.

To all whom it may concern:

Be it known that I, WILLIAM H. VON HACHT, a citizen of the United States, and a resident of Vallejo, county of Solano, State of California, have invented a new and useful Valve Mechanism, of which the following is a specification.

This invention relates to valve mechanisms as used with engines, particularly of the internal combustion type and has to do with the division of such engines known as the overhead valve type.

The principal objects of my invention are to overcome the noisy operation of the overhead valves by the entire elimination of the usual rocker arms and the usual working clearances now provided, also to provide a simpler construction, an improved oiling arrangement, an easier adjustment for the valve lift, a reduction of weight over the generally adopted construction, and means by which the entire valve operating mechanism may be detached from the engine as a unit, for replacement or repairs.

I attain the objects outlined in the overhead valve operating mechanism illustrated in the drawings accompanying this specification in which Figure 1 is a side elevation of a portion of a multi-cylinder internal combustion engine with my valve mechanism in place; Figure 2 is a vertical cross section of the engine cylinder and valve mechanism along the line 2-2 of Figure 1; Figure 3 is an enlarged side view of one of the L-shaped push rods for actuating the valves; Figure 4 is a plan view of the end of the arm of the rod; Figure 5 is an end view of the cam roller carrying lower end of the rod; Figure 6 is a vertical cross section similar to Figure 2 but shows a modification in positioning the cam shaft and rod springs which inverts the action of the rod in respect to the functioning of the valves; Figure 7 shows a modified valve stem connection.

As will be seen by reference to Figures 1 and 2 my valve mechanism contemplates the entire omission of rocker arms, etc. and operates the valves by means of L-shaped push rods (1) slidable up and down in bearings (2) and having an arm (3) projecting at right angles to the sliding portion of the rod over the top of the engine and engaging the stems (3') of the valves (4).

The engine firing chamber is indicated at (5), piston at (6), water circulation space at (7), and spark plug at (8). Figure 2 shows these parts clearly and also at (9) a separate valve mechanism casing bolted 60 to the side of the engine by bolts or studs (10).

This casing (9) may of course be an integral portion of the engine casting (11) but if made separable as indicated it provides for quick removal of the entire valve operating mechanism including the cam shaft, as the L arms of the push rods are slotted at (12) so that when the casing is unbolted it may be pulled off of any studs 70 and away from the valve stem engagement with the slots (12). The casing has an upper, lower, and central horizontal wall as indicated, and in the upper and central are threaded or otherwise secured the bearings 75 (2) for the sliding rods (1).

The rods each have a cam wheel (13) rotatably supported at their lower ends, preferably in a slot (14) formed in the lower end and are positioned directly over 80 a revolvable cam shaft (15) having the usual valve tripping cams formed along it as indicated at (16). The cam shaft has bearing in the casing at several places as indicated at (17) and is coupled at some 85 point not shown in the drawing for operation by the engine through the usual gear or chain drive.

The cams are arranged in the regular way to alternately raise the rods to operate 90 the exhaust and intake valves in the proper sequence and the rods are returned by heavy spiral springs (18) expanding between collars (19) on the rods and the upper bearings (2).

In the design shown in Figures 1 and 2 the action of the rods is the reverse from the push rods in the rocker arm type of valve motion wherein the cam opens the valves, whereas in Figures 1 and 2 the cam 100 closes the valves, that is, the lifting of the rods lifts the arm (3) and thereby carries the valve stem (3') upward, thus closing the valves (4), and upon falling of the cams the spring (18) forces the rods down 105 upon the cams and opens the valves.

As it would be extremely difficult to insure proper seating of the valves at the highest point of the cams I provide an adjustable resilient connection between each 110

valve stem and the arm (3) which moves it.

This is done by threading the rod and screwing thereover a drilled and threaded sleeve (20) having a hexagon head (21) at its outer end and a nut (22) screwed over its lower end, and surrounding the sleeve are two springs (23) and (24), one being above and one below the flattened portion (25) of the slotted arm (3) embracing the sleeve. These springs are under compression through means of the nut (22) and balance the arm (3) between them so that the arm in moving carries the valve in both directions, but they afford a cushion against shock and noise and as against the usual valve clearance and provide for a slight compression of the upper spring to insure a perfect seating of the valve, as the adjustment should be such that the cam lift is slightly in excess of the required amount to seat the valve.

The adjustment is secured by screwing the sleeve (20) up or down on the valve stem and locking it by the nut (26). To prevent the stem from turning it is slotted for a screw driver at (27).

To facilitate inspection of the valve mechanism the outer wall plate (28) of the casing is preferably made separable as indicated; either in whole or in part; and in Figure 1 this wall plate has been omitted to reveal the mechanism described and also to show vertical partitions (29) for stiffening the structure and providing means for supporting the cam shaft bearings (17) and casing stud bolts (10).

The proper lubrication of the parts is effected by maintaining a quantity of oil (30) in the lower part of the casing to submerge the cams and having a pipe (31) leading therefrom to an oil pump (not shown) for pumping it to the upper bearing through the pipe (32) and where it maintains a level (30') to the overflow tubes (33) in the casing, flowing through the bearings or oil overflow tubes to the central partition where the level (30²) is maintained and the same overflow principle is repeated, thus returning the oil to the lower part of the casing for use over again.

A cover (34) extends over the upper portion of the engine to keep out dust and also to convey the oil vapors to the springs (23) and valve stem (3') to provide the slight lubrication which they require.

Figure 3 shows in enlarged elevation a side view of a push rod detached from the casing and with its features described bearing the numerals given. The rod is preferably formed out of a single piece of steel tubing with a rounding bend at (35) and flattened at the valve stem engaging end as indicated.

Figure 4 shows the slot for engaging the sleeve on the stem, but a round hole may

be used instead of the slot in engines where the casing is made integral with the engine, and lateral removal is not contemplated.

To insure a perfectly round push "rod" the tube is preferably turned from the point (36) down to the lower end.

Figure 5 shows the lower end of the tubular rod with cam wheel in place. The tube is slotted at (14) and preferably bushed at (37) to afford a proper support for the cam pivot pin (38).

While the mechanism shown and above described is my preferred arrangement, my invention may assume the form shown in Figure 6 wherein the same elements are shown and numbered with exponents placed on the rearranged members.

In this arrangement the cam shaft (15') is placed above the rollers (16') as indicated so as to push the rods down instead of up, and the spring (18') placed at the bottom of the casing to force the rod upward upon being released by the cam.

This results in the cam opening the valves and the spring closing them, whereas in the first arrangement the cam closes the valves and the spring opens them.

While I show the springs (23) and (24) around the valve stem, in both arrangements, it is apparent that this resiliency could be obtained by several other artifices; one of such might be making the arm (3) itself resilient, or of having the bend (35) of the arm looped or enlarged sufficiently to afford the necessary resiliency, which though important need be very slight in order to insure closing of the valve, and any such modifications coming within the spirit of the invention are intended to be covered in my appended claims.

One of the many possible modifications of resilient valve stem connection is shown in Figure 7, an enlarged sectional detail wherein in the end of the arm (3) instead of having a spring on both sides of it, has a spring on the upper side only to insure resilient closing of the valve but bears directly against the lower of two sleeve nuts (37)—(37) for positive opening of the valve.

I claim:

1. In a mechanism of the character described, a poppet valve having a stem, a cam operated push rod having an arm thereon resiliently engaging the stem, the engagement comprising a sleeve adjustable along the stem embraced by the arm and a spring around the sleeve bearing against the arm.

2. In a mechanism of the character described, a poppet valve having a stem, a cam operated push rod having an arm thereon resiliently engaging the stem, the engagement comprising a sleeve adjustable along the stem embraced by the arm and two springs around the sleeve, one at each side of the arm arranged to bear against the arm.

to hold same in floating relation between them.

3. In an engine having a plurality of overhead valves each with a stem, a push rod for each valve stem, a cam shaft having cams for operating the push rods, a casing entirely supporting the rods and the cam shaft in operative relation, said casing being removably secured to the side of the engine whereby the rods and cam shaft may all be removed without disturbing their operative mounting.

4. In an engine having a plurality of overhead valves each with a stem, a push rod for each valve stem, a cam shaft having cams for operating the push rods, a casing entirely supporting the rods and the cam shaft in operative relation, said casing being removably secured to the side of the engine whereby the rods and cam shaft may all be removed without disturbing their operative mounting, and said rods having each an arm at the upper end extending to its respective valve stem and engaging the same in an open ended slot adapted for lateral withdrawal from the stem in direction of removability of the casing.

5. An overhead valve operating mechanism for an engine embracing a plurality

of poppet valves on the engine having stems, slidable push rods having arms engaging the stems, upper and lower bearings for the slidable push rods, a cam shaft for operating the push rods, springs surrounding the push rods for holding the rods to the cams, a reservoir of oil in which the cams are submerged and a similar reservoir at each bearing and conducting means for circulating the oil successively through the reservoirs.

6. In an engine having an overhead valve with a stem, a cam actuated slidably supported push rod therefor comprising a tube having its upper end bent to form a laterally extending arm reaching to the valve stem, and the extreme end of said tube having its walls brought together to form a flattened portion and there engaging the stem.

7. In an engine having an overhead valve with a stem, a cam actuated slidably supported push rod therefor having a laterally extending arm at its upper end engaging the stem, the engaging portion of the arm having an open ended slot adapting the arm for lateral withdrawal from the stem.

WILLIAM H. VON HACHT.
